[57] CLAIM

The ornamental design for a cover for collapsible infant stroller, substantially as shown and described.

DESCRIPTION

FIG. 1 is a front perspective view of a cover for a collapsible infant stroller showing my invention,

FIG. 2 is a top view showing the cover of the present invention in a planar condition;

FIG. 3 is a similar view to that shown in FIG. 2, but showing the reverse side of the cover of the present invention;

FIG. 4 is a side elevation view of the edge of the cover of the present invention as it appears in FIG. 2; and
FIG. 5 is an enlarged fragmentary view showing the fabric pattern of the cover in greater detail.

The broken lines depicting a stroller in FIG. 1 are for illustrative purposes only.
